US0D1057751S

(12) **United States Design Patent** (10) **Patent No.:** **US D1,057,751 S**
(45) **Date of Patent:** ** *Jan. 14, 2025

(54) **ELECTRONIC DEVICE WITH GRAPHICAL USER INTERFACE**

(71) Applicant: **Apple Inc.**, Cupertino, CA (US)

(72) Inventors: **Kevin Will Chen**, Cupertino, CA (US); **Alan C. Dye**, San Francisco, CA (US); **Nicholas Felton**, Sunnyvale, CA (US); **Aled Williams**, Llandeilo (WS); **Christopher I. Wilson**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/777,265**

(22) Filed: **Apr. 5, 2021**

Related U.S. Application Data

(63) Continuation of application No. 29/663,058, filed on Sep. 11, 2018, now Pat. No. Des. 915,436.

(57) **CLAIM**

The ornamental design for an electronic device with graphical user interface, as shown and described.

DESCRIPTION

FIG. 1 is a front view of a display screen or portion thereof with graphical user interface showing the claimed design; and,

FIG. 2 is a front view of an electronic device having a display screen with the graphical user interface of FIG. 1 applied to the display screen.

The outer broken lines in the figures show a display screen or portion thereof, or an electronic device having a display screen, and form no part of the claimed design.

1 Claim, 2 Drawing Sheets
